UNITED STATES PATENT OFFICE

143,450

DESIGN FOR A SPOON

Frederick K. Storm, Los Angeles, Calif., assignor
to Adel Precision Products Corp., a corporation
of California

Application February 15, 1945, Serial No. 117,961

Term of patent 14 years

(CL D54—12)

To all whom it may concern:

Be it known that I, Frederick K. Storm, a citizen of the United States and residing at Los Angeles, in the county of Los Angeles, State of California, have invented a new, original, and ornamental Design for a Spoon, of which the following is a specification, reference being had to the accompanying drawing, forming part thereof, in which:

Fig. 1 is a side elevation of a spoon showing my new design;

Fig. 2 is a top plan view of the spoon hereof;

Fig. 3 is a longitudinal sectional view of the spoon hereof taken on the line 3—3 of Fig. 2;

Fig. 4 is a rear elevation of the spoon hereof.

Fig. 5 is a side elevation of the complete spoon hereof with the handle shown in broken lines.

The wire mesh shown in part in the central portion of the bowl of the spoon is carried over the open area.

I claim:

The ornamental design for a spoon, substantially as shown and described.

FREDERICK K. STORM.
